UNITED STATES PATENT OFFICE

JOHN H. McDONOUGH, OF DALLAS, TEXAS, AND OLIVER MITCHELL, OF BROOKLINE, MASSACHUSETTS, ASSIGNORS TO THE MURRAY COMPANY, OF DALLAS, TEXAS, A CORPORATION OF TEXAS

COTTON CLEANER

Application filed September 8, 1928. Serial No. 304,756.

Our invention is an improvement upon the machine described in our United States Patent No. 1,495,401, the improvement consisting in providing a connection with an air suction conveyor, from the interior of the casing in such fashion that the functioning of the machine in the desired manner is in no wise interfered with.

In the drawings:

10 Figure 1 is a cross-sectional elevation of a feeder-cleaner;

Figure 2 is an end elevation of the machine shown in Figure 1;

15 Figure 3 is a central, longitudinal sectional view of the air drum, on line 3—3 of Figure 1;

Figure 4 is a perspective view of the gate, on an enlarged scale;

20 Figure 5 is a diagrammatic elevation, indicating the application of our invention to a battery of cleaners;

Figure 6 is an end elevation of the beater drum, on a reduced scale.

In all seed cotton, as it reaches the 25 ginnery, there is more or less leaf trash, dust, sand, shale and other impurities associated with the cotton fibres, which impurities are accumulated during the growth, picking and handling of the cotton, before it reaches the 30 ginnery. In some lots of cotton these impurities are in such quantity and size that special apparatus must be employed to break up the foreign material, particularly bolls, and remove as much as possible, but in such 35 cases the cleaned cotton still contains a considerable quantity of fine impurities which the cleaner, designed for removing larger impurities, is not well adapted to remove.

40 Cotton that has been picked fully matured as well as that which has been snapped in the boll, or pulled after the bolls and foliage are dead and dry, contains some fine foreign matter, and this fine dirt presents a problem for the ginner that has never been fully 45 solved. This leaf trash, shale, sand, etc.

must be eliminated, if at all, before ginning, while the cotton is on the seed, otherwise it becomes tangled in the lint and causes the yarn to break during the spinning process, as carding the cotton does not eliminate this 50 dirt, but merely combs out the cotton fibres in parallelism. This fine dirt, with its effect upon the spinning is the main cause of the low value of bolly, sandy cotton.

Hitherto seed cotton has been cleaned of 55 this fine dirt, by forcibly beating and forcibly dragging over stationary screens of wire mesh or perforated iron, either in free air or with suction continuously applied to one side of the screen, over which screen the cotton was moved by gravity or mechanical means.

60 In our machine, shown in Patent 1,485,401, we proposed to clean the seed cotton of its impurities by subjecting the seed cotton to the action of a hollow perforate spiked drum, rotating in an enclosing casing, the drum actuating the seed cotton against a 65 concentric wire screen, operatively adjacent to the drum and at the same time causing 70 innumerable small air jets, emitted through the perforations of the drum, to press the seed cotton away from the surface of the drum, and against the screen, against which it was rubbed by the motion of the spikes 75 while the air currents passed through the cotton layer blowing particles of dirt and trash through the screen, where the heavier than 80 air particles found their way to the bottom of the casing while the lighter particles remained suspended. The advantages of this 85 cleaning method were very great. The lifting action of the air currents made it possible to surround the actuating drum for the greater part of its circumference with screen 90 against which the drum spikes moved and scraped the seed cotton, so that a drum of given size gave greatly increased screening surface and action, as compared with machines in which the screens were below the 95

drum and extended only opposite the lower part of the drum.

Another principal advantage was the thorough air washing to which every fibre 5 was subjected during transit of the cotton about the drum steadily pressed against the screen by the air currents, and pushed by the drum spikes. Another advantage resided in the fact that the air currents were generated as a by-product of the rotation of 10 the perforated drum, without expense, other than providing open ends for the drum and peripheral perforations for the air emission, the drum, by its centrifugal action upon the 15 air within it, acting as an air pump or fan as well as a support and actuating means for the cotton.

The surface speed of the air drum was greatly in excess of that of the feeder drum 20 so that in operation the incoming cotton, upon the surface of the drum, was reduced to a thin layer easily sustained by the air jets and through which the air jets circulated freely.

25 The disadvantage was that the drum, acting as a centrifugal fan, drew air from outside the casing in which it operated and discharged it within the casing, from which, after being charged with dust and the like 30 in its passage through the cotton, it performed found its way out of the casing, urged by the continual influx of air from without pumped into the casing by the air drum and carrying its dust into the air of the room in which 35 it operated.

In other beater drum cleaners, having the ordinary imperforate drum this effect was not present, since these drums did not inject air into the casing and the fine field dust and 40 other floating particles remained in the casing until they settled to the bottom of the casing to be removed in the ordinary way by the screw conveyor or in some cases to be removed by an ordinary suction air conveyor. In our air emitting drum cleaner a 45 constant current of air passes into and out of the casing, the lighter than air dirt being carried out of the casing in suspension, so that this light dirt does not reach the screw 50 conveyor and the ordinary air suction conveyor could not be employed with a perforated air drum for educating the dust and dirt from the casing, the suction effect being so much more powerful than the air drums 55 emission as to draw air from the lower side of the drum at high speed and correspondingly decrease or neutralize air emission of the upper half of the air drum, thus interfering with the designed operation of screening and air washing by small and relatively 60 slow air jets around the major part of the periphery of the drum.

We have adapted the ordinary suction air conveyor to the evacuation of floating dust 65 and dirt from our cleaner as well as the

heavier dirt which does not remain suspended in air and will now describe our improved machine, using as a type a feeder cleaner for a cotton gin, such as was described in our original Patent No. 1,485,401, 70 but it is to be understood that our invention is applicable to any drum of the perforated, air emitting type, whether embodied in a cotton feeder for gins, or otherwise.

The operation of the feeder-cleaner for 75 gins is well known in the art and need not be described at length.

In Figure 1 is shown a feeder-cleaner, consisting of drum D having a multiplicity of spikes or teeth, d. This drum is set beneath 80 a pair of feed rolls, a', mounted above the drum, D, in a passage, a, of casing A. The drum D and the feed rolls a' rotate as indicated by the arrows. The shaft d' of the drum D and the feed rolls a' are provided 85 with pulleys and gears, outside the casing, by means of which they are actuated from a source of power, all as is well known.

To one side of the drum D is arranged 90 an auxiliary drum or drums, 1, within a screened casing, 2, 3, the screen being indicated by 2 and the casing by 3. Drum 1 is carried by shaft 11 mounted in bearings 12 in the sides or ends of casing 3. The ends of drum 1 are open ended as at 1^a, and the 95 peripheral walls 1^b of the drum are perforated as at 1^c.

When the open end, perforated drum is rotated, in operation, the air within the drum is frictionally rotated therewith and is condensed at the inner surface of the drum and attenuated at the axis of the drum. Air consequently escapes from the drum through the perforations 1^c and enters the drum axially at the open ends, 1^a. 100

To increase this action we provide the drum at its ends with the inwardly extending flanges or skirts, 1^d, which, in operation, restrain any escape of air from the ends of the drum at the inner surface and restrain also 110 the entrance of air except at the opening, 1^a. In practice, we form in the casing, opposite the drum opening, 1^a, an opening 3^a around the bearings 12, to admit the easy entrance of air at this point, to the interior of the 115 casing and drum.

To further increase the action we may employ fan blades, F, rotating around the shaft 11. The face of these blades may be parallel to the axis of the drum and shaft or, preferably, the free ends of the blades may be turned somewhat from across the direction of rotation, to partially face away from the ends of the drum and actuate the air toward the interior of the drum, as well as to the 125 inner periphery of the drum.

Our invention is applicable to the feeder drum D, or any other drum, but is shown only as applied to an auxiliary drum, 1.

The drums are connected to rotate in uni- 130

son by suitable pulleys h and belt h' and a screw conveyor, C, may be mounted beneath the screen, within the casing, and driven by pulley c' , to evacuate the heavy non-floating 5 dirt and trash removed from the seed cotton in the cleaning process.

At the lower part of the casing, where the walls of the casing form a trough, in which the screw conveyor is mounted, at 10 one end of the casing, an exit, 51, is formed and to this exit the screw conveyor moves all heavy dirt, which is pushed through the exit. This exit 51 communicates with a pipe 52 communicating meditately or immediately 15 with the suction side of a centrifugal air fan 53, the fan being also provided with an eduction pipe 54 leading to the outer air or as desired. It will now be apparent that operation of the fan 53 will draw air from 20 and through the casing 3 and the drum 1 and, as has been explained, this effect is completely disturbing to the normal and de- 25 signed operation of the machine. To overcome this difficulty we provide preferably in the pipe 52 adjacent to the outlet or exit 30 51, an opening 55 admitting air to the pipe and to the fan. This opening may be of a designed capacity, such that the effect of the fan upon the casing air is to create merely a drift to the exit 51 and the pipe 52. As there are variations in the air moving 35 capacity of fans and as additional cleaner feeders may be connected to the fan in series from time to time, we prefer to pro- 40 vide the opening 55 with an adjustable gate by which the volume of air entering the opening 55 to feed the fan may be nicely regulated to give the desired air movement within the casing 3. The gate is shown as 45 a box 56 open on one side to the pipe 52 and on the other to the air, the latter opening having a sliding door 56^a by means of which the opening may be varied as needed to obtain the desired effect.

45 We have shown our invention as applied to a single cleaner feeder, but it may be applied to a battery of feeders, by employing tubular connection connecting the several casings, the feeder casing exit at one end 50 of the line being connected to the pipe 52 and the fan suction being effective as de- 55 scribed in the several casings. If desired a single screw conveyor may run through several casings to move the heavy dirt to the exit 51 and pipe 52. It will be noted 60 that the air and dust evacuation from the casing 3 is entirely independent of the heavy dirt evacuation by the screw conveyor. The screw conveyor may be operated only at in- 65 tervals if desired or may be dispensed with and the heavy dirt removed at intervals by hand. In either case the air and dust eva- 70 cuation would proceed so long as the fan-drum 1 and fan 53 were in operation.

75 765 The operation is as follows: The machine

being actuated from a source of power, seed-cotton is passed into the feeder-cleaner at, c, usually from a cotton chute under which the machine is disposed and the seed cotton is engaged by the rollers, a' a', and slightly 70 compressed into a loose bat. The bat is received by the drum D, turning as indicated by the arrows, Figure 1, and moved by spikes, d, against the drum 1, rotating as indicated by arrow, by the spikes, d, on 75 which drum 1, the bat is carried around opposite screen 2, which begins, as shown, over the drum 1, and extends to the exit e, of the casing and feeder cleaner.

80 As the bat so deposited upon the surface of drum 1 is carried forward air from the drum is emitted through the perforations 1^c beneath the cotton and tends to lift and open and hold it against the screen 2, the air passing through the cotton and the screen, carrying dust and trash from the cotton and moisture, if any. The screen 2 is preferably 85 so spaced from the drum that the cotton cannot be forced by the outwardly moving air, beyond the ends of the spikes, d. The cotton is pushed along by the spikes d, and held and rubbed against the screens 2, until it reaches point 21, between drums, when the bat passes to drum D, which pushes it to the exit, e, and the chute, g, from which it 90 passes to the gin, indicated at G.

95 During this passage of the cotton from inlet to outlet it is held toward the screen 2 either against gravity by the air currents, or by the air currents, aided by gravity when the cotton is below the center of the drum, and the cotton is subjected not only to the cleaning action of the spikes and screen but, as well, the cleaning action of the air passing 100 through the cotton and the screen.

105 The heavier-than-air dirt from the seed cotton passes by gravity to the bottom of the casing 1 and the screw conveyor C, if a screw conveyor is employed. The dirt and dust held in suspension in the air outside the screen 2 drifts with the air to the exit 51 and pipe 52 and joins the strong air current within the pipe and so is carried to and beyond the fan 53.

110 The motion of the dust laden air within the casing is controlled to a nicety by adjustment of the gate or door 56^a to permit a greater or less proportion of the air capacity of the fan 53 to be supplied through the gate 56 and a greater or less proportion 115 in consequence through the exit 51 from within the case 1.

120 Our invention may be easily and cheaply applied to existing machines of the type de- 125 scribed and will convert such machines into dustless machines to the sanitary benefit of the establishments where the machines are employed and in cases where many machines are employed in a confined space will eliminate any risk of dust explosions.

It will be observed that our preferred suction means are so arranged that, where this is necessary, the air movement induced by the suction fan 53 is sufficiently slow to offer no interference with the action of the air emitting drum 1 while in the pipe 52 it is rapid enough to carry the heavy dirt moved by the screw conveyor C together with the dust and dirt in suspension, through the necessary length of pipe to the fan and thereafter through the eduction pipe 54 to the outer air or elsewhere. It will also be observed that in our device two air moving devices of widely differing powers are combined 15 in such fashion that the greater force does not dominate nor interfere with the free and perfect operation of the lesser force.

In Figure 5 we have indicated the application of our invention to several cleaners, 20 arranged in series, the several cleaners communicating with each other and the suction pipe and fan and the several cleaners also being provided with a screw conveyer, running the length of the battery. The connecting tubes between the several casings 3, 25 are marked 3*.

The pipes 52 and 54 should preferably be of such size as to have a capacity for free 30 passage of air equal to the capacity of the fan 53 for moving air and the gate 56 when fully open should have a capacity equal or superior to the pipe 52, so that full opening of the valve 56^a will provide full air supply for the fan 53, without drawing air through 35 the exit 51 of the casing 3. Gradual closing adjustment of the valve 56^a will gradually restrict air entry to the fan through opening 55 and cause the fan suction to become gradually more effective in drawing air 40 through exit 51 of casing 3, until, if valve 56^a were entirely closed, all the supply of air for fan 53 would be drawn through exit 51. It is obvious therefore, that adjustment of valve 56^a from open to closed will give 45 any desired air suction within casing 3, from nothing to the full capacity of the fan, between the limits of movement of the valve 56^a.

We have shown the preferred organization 50 of the suction elements and suction control, the gate 56 being situated in the suction pipe 52 between the fan and the connection of the pipe 52 with the case 3 and adjacent the exit 51. This arrangement 55 gives absolute control of the air movements within the casing.

We claim:

1. In a cotton cleaner, in combination, an outer casing having air openings; a peripherally perforated drum, its ends open for air inlet, mounted for rotation in the casing, its open ends opposed to the casing air-opening; means for rotating the drum; a suction pipe connected to the cleaner and 60 communicating with the interior of the cas- 65

ing; an air opening of fixed area adjacent the suction pipe connection to the cleaner admitting air to the suction pipe; means to create a suction in the pipe.

2. In a cotton cleaner, in combination, 70 an outer casing having air openings; a peripherally perforated drum, its ends open for air inlet, mounted for rotation in the casing, its open ends opposed to the casing air-opening; means for rotating the drum; 75 a suction pipe connected to the cleaner and communicating with the interior of the casing; an air opening of fixed area admitting air to the suction pipe; means to create a suction in the suction pipe. 80

3. In a cotton cleaner, in combination, 85 an outer casing having air openings; a peripherally perforated drum, its ends open for air inlet, mounted for rotation in the casing, its open ends opposed to the casing air-openings; means to rotate the drum; a suction pipe having suction communication with the interior of the casing; an air opening for admitting air into the pipe; means to govern the admission of air through this 90 opening; means to create a suction in the suction pipe.

4. In a cotton cleaner, in combination a multiplicity of cotton cleaners, each comprising an outer casing having inlet air 95 openings; a peripherally perforated drum, its ends open for air inlet, mounted for rotation in the casing, its open ends opposed to the casing air-openings; means to rotate the drum; and air pipes connecting the interiors of the several casings; a suction air pipe having suction communication with the interior of the casing; an opening for admitting air into the pipe; means to fix the area of the opening for 100 the admission of air through the opening; means for creating a suction in the suction pipe. 105

5. In a cotton cleaner, in combination, a multiplicity of cotton cleaners, each comprising an outer casing having air openings opposed to the ends of an air drum; that air drum peripherally perforated, its ends open for air inlet, mounted for rotation in the casing, its open ends opposed to the casing air-openings; means to rotate the drum; and air pipes connecting the interiors of the several casings; a suction air pipe having suction communication with the interior of the casings; an opening for admitting air into the pipe; means to fix the area of the opening, for the admission of air; means for creating a suction in the suction pipe. 110 115 120

6. In a cotton cleaner, in combination, an outer casing having air openings; a peripherally perforated drum, its ends open for air inlet; mounted for rotation in the casing, its open ends opposed to the casing air-openings; a suction pipe connected to 125 130

the casing and communicating with the interior of the casing; a suction fan connected to the suction pipe; an air opening in the suction pipe between the fan and the 5 pipe connection to the outer casing; means to fix the area of the opening for the entrance of air into the suction pipe.
